UNITED STATES PATENT OFFICE.

HENRY A. WEIHMAN, OF PHILADELPHIA, PENNSYLVANIA, ASSIGNOR TO
SIMONS BRO. & CO., OF SAME PLACE.

DESIGN FOR A BACK FOR BRUSHES OR SIMILAR ARTICLES.

SPECIFICATION forming part of Design No. 33,121, dated August 28, 1900.

Application filed August 1, 1900. Serial No. 25,597. Term of patent 3½ years.

To all whom it may concern:

Be it known that I, HENRY A. WEIHMAN, of the city and county of Philadelphia, State of Pennsylvania, have invented a new and original Design for Backs of Brushes or Similar Articles, of which the following is a specification.

My new design for backs of brushes and similar articles is shown in the accompanying drawings, in which—

Figure 1 is a plan view of the back of a brush, showing my improved design; and Fig. 2 is a longitudinal section on line 2 2 of Fig. 1, showing the general extent of the relief-work thereof.

The general conformation or outline of the back is pandurate, and the leading features of the ornamentation thereof comprise the smooth central surfaces A G G, around which and across at intervals is arranged a floral design H B C. The outer boundary D of the article is also made smooth and separated from the central smooth portions by a slightly-recessed stippled or chased portion E, so as to make the central parts more independent

and marked. The floral design is very highly embossed, so as to make it stand out in high relief. As additional ornamentation, the outer smooth boundary part D of the article has at the parts E, F, J, and L, scroll ornamentation, arranged to blend more or less with the floral design and add to the richness of the effect. The extreme lower end of the handle portion is finished with a shell ornamentation K. The back for the brush portion has the design only upon one side, whereas the handle portion for the brush, or that portion below the dotted line x x, is made double or similar on both sides, as indicated in Fig. 2.

Having described my invention, what I claim as new, and desire to secure by Letters Patent, is—

The design for backs of brushes and similar articles, as herein shown and described.

In testimony of which invention I have hereunto set my hand.

HENRY A. WEIHMAN.
